UNITED STATES PATENT OFFICE.

ALVA J. FISHER, OF EVANSTON, ILLINOIS.

COOLING DEVICE FOR INTERNAL-COMBUSTION ENGINES.

SPECIFICATION forming part of Letters Patent No. 760,581, dated May 24, 1904.

Application filed December 8, 1902. Serial No. 134,419. (No model.)

To all whom it may concern:

Be it known that I, ALVA J. FISHER, a citizen of the United States, residing at Evanston, in the county of Cook and State of Illinois, have 5 invented certain new and useful Improvements in Cooling Devices for Internal-Combustion Engines, of which the following is a specification.

My invention relates to improvements in 10 explosive or internal-combustion engines, and particularly to such engines when organized to operate as self-acting air-compressors.

An object of my invention is to provide improved means whereby the piston-rod of an 15 internal-combustion engine may be carried directly through the explosion-chamber of the engine.

Another object of my invention is to shorten, 20 lighten, cheapen, and make more efficient an engine of the construction described.

Another object of my invention is to provide an improved form of self-cooling water-jacketed piston-rod.

These and such other objects as may hereinafter appear are shown in the accompanying 25 drawings, in which—

Figure 1 shows my preferred construction of a self-acting air-compressing internal-combustion engine. Fig. 2 is a sectional plan view 30 thereof on the section-line indicated in Fig. 1. Figs. 3, 4, and 5 are enlarged sectional details, Fig. 5 being a section on the line 5 5 of Fig. 3. Fig. 6 is a detail sectional view of a modification. Fig. 7 is a sectional detail of the 35 parts shown at the right end of Fig. 3, showing the piston at the extreme of its outward stroke. Figs. 8 and 9 are details of modified forms of 40 my invention. Fig. 10 is a side elevation of a modification, and Fig. 11 is a plan view of Fig. 10 on the line 11 11 of Fig. 10.

Like characters of reference indicate the same parts in the several figures of the drawings.

Taking for illustration a gasoline-engine, A 45 is the cylinder-casing, provided with the usual water-jacket at B and provided at each end with cylinder-heads C C' of a usual type, said cylinder-heads being also water-jacketed at b.

Fitted within the cylinder is the piston-head D, dividing the interior of the cylinder into two 50 explosion-chambers E and F, respectively.

The engine is provided with any familiar and convenient type of apparatus for charging the explosion-chamber with charges of explosive material, for igniting the same at proper 55 intervals, and for taking care of the exhaust, &c., these details forming no part of my invention, and being familiar to those skilled in this art they are not here shown.

In the embodiment of my invention shown 60 in the drawings the piston-rod G extends through a stuffing-box H and a gland I in the piston-head C and connects with a yoke J, to which cranks leading to the fly-wheels are attached in a familiar manner. In like manner 65 the piston-rod K extends in the opposite direction through a stuffing-box L and gland M in the piston-head C'; but instead of connecting with a yoke, &c., it extends beyond the piston-head C' and through a gland N, a 70 stuffing-box O in one head P of the air-pump cylinder Q, and into the piston-head R, fitted within the air-compressing cylinder. This cylinder is water-jacketed at q in a familiar 75 manner and is provided with any suitable inlet and discharge valves, which are not shown, as the same constitute no part of my invention. The air-compressing cylinder is fitted with a head and intake and discharge valves at each end thereof, so as to be a double-acting 80 compressor. Screwed into the piston-head K and extending therefrom in a direction opposite to the piston-rod K is a piston-rod S, which ends in a stuffing-box T.

The piston-rods G, K, and S are hollow, and 85 their adjacent ends abut against each other or are so arranged within the piston-heads D and R as to form a continuous tube from the stuffing-box T on the piston-rod S to the end of the piston-rod G, which is connected with a 90 yoke J, the piston-rod G being closed at or adjacent to this end in any suitable manner— as, for instance, in the manner shown at the right end of Fig. 3, where it is screwed into a socket in the yoke J and against any suitable packing-ring. The stuffing-box T upon 95

the end of the rod S is mounted upon a tube U, which is mounted at one end within a casting V and extends through the piston-rods S K G and ends, preferably, within the piston-rod G at a point beyond the inner face of the cylinder-head C. This tube U is of considerably less diameter than the piston-rods S K G, so that an annular water chamber or space is provided between the tube U and the piston-rods.

The end of the tube U, secured within the casting V, communicates with a chamber v, from which an outlet-port leads to the water-pipe W. X is a tube of smaller diameter than the tube U, which connects at one end directly with a supply-pipe Y, provided with a one-way check-valve y, which allows water to flow into the pipe X. The pipe X extends through the pipe U for substantially its entire length, as shown in Fig. 3.

The discharge-pipe W is provided with a one-way check-valve w, arranged to allow the passage of water therethrough from the chamber v. This pipe connects with the water-jacket q of the air-compressor cylinder Q, while the pipe Z leads from the water-jacket q of the compressor Q to the water-jacket R of the engine-cylinder A. From such water-jacket the pipe a leads and may be arranged, if desired, to connect with a tank from which the water-supply is drawn through the pipe Y, thus arranging a complete circulation which will permit the same water to be used over and over again without waste.

As so arranged, my device operates as follows: Taking the position shown in Fig. 2 as the initial position of the parts, the first movement of the piston-head D to the right will carry the piston-rods S K G with it, (see Fig. 7,) and these hollow rods, acting as a pump, will draw through the pipes Y X sufficient water to fill the chambers within the piston-rods and within the pipe U. Consequently the piston-rods K G where they pass through the explosion-chambers E F, in which they are subjected to a high degree of heat, are internally water-jacketed and are thereby kept sufficiently cool for the operation of the machine. As an explosion within the chamber F carries the piston-head D to the left, and with it the hollow piston-rods S K G, the water-chamber within the piston-rod G beyond the end of the tube U is reduced in volume and the water therein is forced backwardly.

By reason of the check-valve y the water cannot return in that direction, and so is forced through the check-valve w and pipe W and into the water-jacket q of the compression-chamber. The continued action of the apparatus then forces the water from the water-jacket q into the water-jacket B and then into the pipe Z either to any convenient point of discharge or back to the tank from which the supply was originally obtained. It will thus

be seen that the water as it first comes from the tank is used to internally water-jacket the piston-rods K G, which are subjected to the highest degree of external heat and which it is most important to keep cool.

In Fig. 6 I have shown a modification of my device, showing the parts broken away, as in Fig. 3, the parts of the device between the broken sections in Fig. 6 being substantially the same as like parts shown in detail in Fig.

3. In this modification the casting V is elongated, so that the chamber v', while serving the same purposes as the chamber v in Fig. 4, is elongated so as to form a cylinder or barrel, upon the end of which is mounted a stuffing-box T', through which the hollow piston-rod S reciprocates. By this construction I obtain a larger pump, and so an increased flow of water through the piston-rod and the water-jackets, and I am enabled to dispense with the tube U, thus simplifying the device and at the same time increasing its effectiveness without departing from the spirit of my invention.

In the modification shown in Figs. 10 and 11 I also dispense with the tube U, as well as with the chamber v. The feed-pipe Y passes into the casting V², where it connects with the pipe X. This pipe projects through the stuffing-box T, mounted on the hollow piston-rod S, and into the piston-rod S a distance slightly greater than the length of the stroke of the piston. In this modification instead of having the passage through the piston-rods S K G terminate within the cross-head J it continues through the cross-head, which I shall here call J', and connects with a pipe 3, 100 which in turn connects with the pipe 4. This pipe 4 is arranged parallel with the hollow piston-rod G and is arranged to reciprocate through a stuffing-box 5 in a barrel or cylinder 6, from which pipe Z' leads into the bottom 105 of the water-jacket B, from which in turn the pipe W' leads into the bottom of the water-jacket q, from which the pipe a' leads to a point of discharge or to the supply-tank, as may be preferred. With this arrangement a simple and direct circulation through the piston-rods, water-jackets, and piston-heads is obtained, as with this arrangement I prefer to make the piston-head D' hollow, and I obtain a double-pumping action—that is, in the 110 hollow piston-rod S and in the chamber or pump 6.

In Fig. 9 I have shown the engine A arranged to be made single-acting, in which event the cylinder-head C is dispensed with, 120 the tubes U and X terminate short of the piston-head D², and I supply a pitman G' in place of the piston-rod G.

In Fig. 8 I have shown another modification, in which the tube X is dispensed with and the tube U is connected, by means of a T-coupling, 125 direct to the supply-pipes W and Y.

Other modifications will suggest themselves

to meet various conditions and exigencies of shop convenience without departing from the spirit of my invention.

I claim—

- 5 1. In a device of the class described, the combination with an explosive-engine and a pump arranged tandem therewith, of a hollow connecting means extending from the engine-piston to a cross-head connecting with fly-wheel mechanism, and extending in the opposite direction through the end of the engine-cylinder and through the pump-piston so as to constitute the piston-rod of the pump, a casing secured to the end of the pump-cylinder 15 farthest away from the engine, and provided with a fluid-passage, a tube secured to said casing, connecting with said fluid-passage, and extending longitudinally within said hollow connecting means, a stuffing-box secured to 20 said hollow connecting means and mounted upon said tube, and a fluid-conduit extending through said casing and into said tube, substantially as described.

2. In a device of the class described, the combination with the cylinder of an internal-combustion engine provided with a water-jacket, of a piston arranged in said cylinder so as to divide the same into two explosion-chambers, a hollow piston-rod extending from said piston 30 through one explosion-chamber and through the cylinder-head forming the stationary end of said explosion-chamber and connecting with a cross-head connecting with fly-wheel mechanism, a pump arranged tandem with said cylinder, and provided with a water-jacket, a second hollow piston-rod extending through the other explosion-chamber in said cylinder and through the cylinder-head forming the stationary end of said explosion-chamber and connecting said piston with the pump-piston, and also connecting with said first hollow piston-rod, a third hollow piston-rod connecting with the second piston-rod and with the pump-piston, and extending oppositely from said second piston-rod, a stationary fluid-conduit leading from a source of fluid-supply and extending within said third piston-rod, and means for making a water-tight connection between said conduit and said piston-rod, and tending oppositely from said second piston-rod, a stationary fluid-conduit leading from a source of fluid-supply and extending within said third piston-rod, and means for making a water-tight connection between said conduit 45 and said piston-rod.

3. In a device of the class described, the combination with an internal-explosion engine provided with a water-jacket, of a pump ar-

ranged tandem therewith, and also provided with a water-jacket, a hollow connecting means connecting the engine-piston with the pump-piston, a tube carried by the pump-piston, a stationary fluid-conduit extending through said tube and through the greater part of the length of said hollow connecting means, means for making water-tight connection between said tube and said conduit, and means for conducting the fluid from said hollow connecting means through the water-jackets of said pump and engine. 65

4. In a device of the class described, the combination with the cylinder of an internal-combustion engine provided with a water-jacket, of a piston arranged in said cylinder so as to divide the same into two explosion-chambers, 70 a hollow piston-rod extending from said piston through one explosion-chamber and through the cylinder-head forming the stationary end of said explosion-chamber and connecting with a cross-head, a pump arranged 75 tandem with said cylinder, and provided with a water-jacket, a second hollow piston-rod extending through the other explosion-chamber in said cylinder and through the cylinder-head forming the stationary end of said explosion-chamber and connecting said piston with the pump-piston, and also connecting with said first hollow piston-rod, a third hollow piston-rod connecting with the second piston-rod and with the pump-piston, and extending oppositely from said second piston-rod, a stationary fluid-conduit leading from a source of fluid-supply and extending within said third piston-rod, means for making a water-tight connection between said conduit and said piston-rod, a stationary casing arranged adjacent to the engine-cylinder, a second fluid-conduit connecting with and extending from said first piston-rod and arranged to movably connect with said casing, means for making a 85 water-tight connection between said conduit and said casing, means connecting said casing with the water-jacket of said cylinder, means connecting the water-jacket of said cylinder with the water-jacket of said pump, and a 90 discharge-conduit leading from the water-jacket of said pump. 100
